US0D1103168S

(12) **United States Design Patent** (10) **Patent No.:** **US D1,103,168 S**
(45) **Date of Patent:** **** Nov. 25, 2025**

(54) **PORTABLE HARD DRIVE**

(71) Applicant: **Xuepeng Huang**, Guangdong (CN)

(72) Inventor: **Xuepeng Huang**, Guangdong (CN)

(**) Term: **15 Years**

(21) Appl. No.: **29/963,566**

(22) Filed: **Sep. 18, 2024**

(30) **Foreign Application Priority Data**

Sep. 11, 2024 (CN) 202430579858.2

(51) **LOC (15) Cl.** **14-02**

(52) **U.S. Cl.**

USPC **D14/348**

(57) **CLAIM**

The ornamental design for a portable hard drive as shown and described.

DESCRIPTION

FIG. 1 is a perspective view of a portable hard drive showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the portable hard drive that form no part of the claimed design.

1 Claim, 8 Drawing Sheets
